DISTRIBUTOR FOR STOKERS

Elmer F. Seibel and Alfred Hutton, Erie, Pa., assignors to The Standard Stoker Company, Incorporated, a corporation of Delaware

Application December 15, 1937, Serial No. 179,902

8 Claims. (Cl. 110—105.5)

This invention relates to stokers and more particularly to improvements in the fuel distributing member of a stoker of the type that communicates with the firebox through a firing opening in a wall thereof above the level of the firebox grate.

In stokers of this type, the distributing member projects a distance into the firebox and is consequently subjected to a high degree of heat, causing the forward portion thereof to burn away and necessitating frequent replacement of the distributing member. It is, therefore, the main object of this invention to provide the distributing member of a stoker of the type described with improved means for cooling and prolonging the life thereof.

Another object of the invention is to provide a novel combination and arrangement of the means for cooling and prolonging the life of the plate, with the plate, so that it can be conveniently removed and easily replaced and secured in position.

Other advantages and objects of the invention will become apparent from the following description, and from the appended claims and drawings, in which,

Fig. 1 is a fragmentary vertical central sectional view of a firebox and stoker embodying a preferred form of the invention, the latter being shown in elevation;

Fig. 2 is a plan sectional view on the line 2—2 of Fig. 1;

Fig. 3 is an end elevation of the distributing member of the stoker;

Fig. 4 is a sectional view on the line 4—4 of Fig. 2;

Fig. 5 is a sectional view on the line 5—5 of Fig. 2; and

Fig. 6 is a sectional view on the line 6—6 of Fig. 1.

While the novel distributing member may be used with various types of furnaces, it is especially adapted for use with a locomotive firebox and it has, therefore, been shown so applied in the drawings. In the drawings, only so much of the stoker has been shown as is essential to a complete understanding of the invention.

The rear wall or water leg of a locomotive boiler is fragmentarily shown and designated by the numeral 10 and comprises the inner and outer sheets 11 and 12, respectively. A firing opening 13 of the conventional form used on stoker fired locomotives is provided in the rear wall 10.

The stoker, designated generally by the nu-

meral 14, comprises a riser conduit 15 which extends upwardly and is curved forwardly for delivering fuel through the opening 13 onto a distributor plate 16. The conduit 15 is provided with a movable section 17 hinged at its lower portion to the body of the conduit, as at 18, forming with the firedoor 19 a closure for the opening 13.

Suitable means is provided for rigidly attaching the distributor plate 16 to the riser conduit 15. As best shown in Fig. 2, the lower wall 20 of the conduit 15 is provided with a recess or cut-away 21, into which is fitted the reduced portion 22 of the distributor plate 16. A plurality of screws 23 are adapted to hold the parts in assembled relation.

Fuel projecting means, in the form of a steam nozzle 24 having a plurality of jet apertures 25 therein, is secured in position in a recess 26 between the lower wall 20 of the riser conduit and the rear side of the distributor plate 16. Suitable means, such as the laterally spaced diverging ribs 28 and the centrally disposed V-shaped block 29, are provided on the fuel supporting surface of the distributor plate 16 for deflecting fuel to all parts of the firebed in the firebox 30.

Formed with and projecting laterally beyond the sides of the distributor plate 16 and below the level of the top surface thereof are the ledges 31 and 32. A ledge 33 also extends forward of the front of the plate 16 below the level of the top surface thereof. The ledges 31 and 32 are provided on that portion of the plate 16 that projects into the firebox. The ledge 33 is shown along only a portion of the forward end of the plate 16, but the lateral extent of this ledge can be increased or decreased, as desired, according to the weight that it is to support.

A skirt 34, suspended from the ledges 31, 32 and 33, protects the portion of the plate 16 that is ordinarily exposed to the fire. The skirt 34 comprises a front wall 35 depending from the forward edge of the distributor plate, a pair of side walls 36 and 37 depending from the side edges of the plate and a rearwardly and downwardly sloping bottom wall 38 joining with the lower edges of the front and side walls 35, 36 and 37. The front wall 35 and side walls 36 and 37 are provided along their upper edges with the inturned flanges 39, 40 and 41, respectively, which rest upon the ledges 33, 31 and 32, respectively, forming a support for the skirt 34. The walls 35, 36, 37 and 38 of the skirt 34 define with the plate 16 a chamber 42 open at its rear-

ward end, through which opening a current of air is drawn from outside the firebox due to the draft in the firebox.

The skirt 34 is arranged, when assembled in the firebox with the distributor plate 16, to have the rearward edges of its side walls 36 and 37 and bottom wall 38 closely adjacent the plane of the inside sheet 11 of the firebox rear wall 10. A plurality of perforations 43 are provided in the front, side and bottom walls of the skirt 34, through which air is drawn from the chamber 42 into the firebox. The draft in the firebox draws a current of outside air to the firebox through the entrance 44 beneath the distributor plate 16, the air in its passage through the chamber 42 and perforations 43 impinging against the distributor plate 16 effecting a cooling action that protects the portion of the plate ordinarily exposed to the fire from burning away.

In order to secure the skirt 34 in assembled relation with the distributor plate 16, pins 45 are provided passing through the vertically aligned holes 46 and 47, formed respectively in the plate 16 and the flanges 48, 49, which extend into the chamber 42 from the side walls 36, 37, respectively, of the skirt 34. Each of the pins 45 is provided with an enlarged head 50 which fits into a counterbored recess 51 formed in the plate 16 near its side margin concentric with the vertically aligned holes 46 and 47. The enlarged heads of the pins 45 do not protrude above the upper surface of the plate 16, and each is provided with a bail 52 for conveniently removing them whenever it is desirable or necessary to disconnect the skirt 34 from the plate 16.

The skirt 34 thus provides protection for the plate 16 against the intense heat of the firebox and is arranged to be easily removed when necessary to make repairs or replacement thereof without dismantling or disturbing any other parts of the stoker.

We claim:

1. In combination, a stoker fuel distributing table comprising a table top arranged to permit fuel to pass thereover for distribution, said table having ledge-like means extending outwardly from the sides thereof in a plane below the plane of the table top, a detachable shield for said table having an inturned flange resting on said ledge-like means for supporting said shield, ledges formed with said shield below the level of said flange extending beneath said table, and means extending loosely through said table and ledges for restraining displacement of said shield with respect to said table.

2. In combination, a stoker fuel distributing table comprising a table top arranged to permit fuel to pass thereover for distribution, said table having ledge-like means extending outwardly from the sides and front end thereof in a plane below the plane of the table top, a detachable shield for said table having an inturned flange resting on said ledge-like means for supporting said shield, ledges formed with said shield below the level of said flange extending beneath said table, and means extending loosely through said table and ledges for restraining displacement of said shield with respect to said table.

3. In combination, a stoker fuel distributing table comprising a table top arranged to permit fuel to pass thereover for distribution, said table having ledge-like means extending outwardly from the sides and front end thereof in a plane below the plane of the table top, and a detachable concave shield for said table having an

inturned flange resting on said ledge-like means for supporting said shield, said concave shield and said table defining a chamber open at its rearward end for admission of a cooling fluid for protecting that portion of the distributing table that when in use is exposed to the intense heat of a firebox, ledges formed with said shield extending inwardly of said chamber beneath each side of the table, and means extending vertically loosely through said table and said ledges for restraining displacement of said shield with respect to said table, said shield being provided with a plurality of closely spaced perforations for the emission of the cooling fluid from said chamber.

4. In combination, a stoker fuel distributing table comprising a table top arranged to permit fuel to pass thereover for distribution, said table having ledge-like means extending outwardly from the sides and front end thereof in a plane below the plane of the table top, a detachable shield having front and side walls embracing corresponding portions of said table and a bottom wall joining said front and side walls, said shield having an inturned flange resting on said ledge-like means for supporting said shield, the walls of said shield and said table defining a chamber open at its rearward end, the side walls of said shield having ledges formed therewith extending inwardly of said chamber beneath said table, and means extending vertically loosely through said table and said ledges for restraining displacement of said shield with respect to said table.

5. In combination, a stoker fuel distributing table comprising a table top arranged to permit fuel to pass thereover for distribution, said table having ledge-like means extending outwardly from the sides thereof in a plane below the plane of the table top, a detachable concave shield for said table having an inturned flange resting on said ledge-like means for supporting said shield, said concave shield and table defining a chamber open at its rearward end, ledges formed with said shield and extending inwardly of said chamber beneath each side of the table, and means extending vertically loosely through said table and said ledges for restraining displacement of said shield with respect to said table.

6. In combination, a stoker fuel distributing table comprising a table top arranged to permit fuel to pass thereover for distribution, said table having ledge-like means extending outwardly from the sides and front end thereof in a plane below the plane of the table top, a detachable concave shield for said table having an inturned flange resting on said ledge-like means for supporting said shield, said concave shield and table defining a chamber open at its rearward end, ledges formed with said shield and extending inwardly of said chamber beneath each side of the table, and means extending vertically loosely through said table and said ledges for restraining displacement of said shield with respect to said table.

7. In combination, a stoker fuel distributing table comprising a table top arranged to permit fuel to pass thereover for distribution, said table having ledge-like means extending outwardly from the sides thereof in a plane below the plane of the table top, a detachable concave shield for said table, said shield having an inturned flange at its upper marginal edge arranged to seat on said ledge-like means for supporting the shield from said table, said concave shield and table

defining a chamber open at its rearward end, ledges formed with said shield and extending inwardly of said chamber beneath each side of the table, and means extending vertically loosely through said table and said ledges for restraining displacement of said shield with respect to said table.

8. As an article of manufacture, a shield for a stoker fuel distributing table comprising side walls, a front wall and a bottom wall, said shield

5 having an open top and an open rearward end, said front and side walls having inturned flanges at their respective upper edges, said side walls having inwardly extending ledges below the level of said flanges, and an opening extending vertically through said ledges, said side, bottom and front walls being provided with a plurality of apertures.

ELMER F. SEIBEL.

ALFRED HUTTON.
